PLUG AND DEAD END RECEPTACLE

Nils A. Tornblom, Chicago, Ill., assignor to Appleton Electric Company, a corporation of Illinois

Application April 1, 1936, Serial No. 72,045

2 Claims. (Cl. 173—328)

The present invention may be said to have two main objects which are, first, to provide the receptacle member of a separable connector with means to "dead-end" it upon the separation of the plug member therefrom; and, second, to break the electrical connections within enclosed spaces or chambers, whereby the formation of arcs cannot cause the ignition of gases surrounding the device as a whole.

10 In carrying out my invention I so construct and arrange the cooperating contact elements that the arcs formed upon the withdrawal of the plug member will be broken before they can be reached by outside gases, and provide the receptacle with a shield that normally covers and conceals the contact elements in the receptacle; the cover or shield being provided with openings through which the contact elements on the plug must pass to reach the cooperating elements in the receptacle; and making it necessary that the shield be moved from its normal protective position, after the contact elements on the plug have been entered in the openings therein, to bring such openings into registration with the contact elements in the receptacle. Thus, the plug goes through three steps in making a connection, the first step being that of engaging its contact elements in the openings in the shield, the second step being that which causes the shield 20 to be moved from its normal position, and the third step being that which permits the contact elements to be brought into engagement with the contact elements in the receptacle. Means are also provided to prevent the complete withdrawal 30 of the plug from the receptacle, excepting through these same three steps, carried out in the reverse order, however. The shield gives the "dead end" effect to the receptacle upon the removal of the plug, and the provision for compelling the three-step movements of the plug insures that arcs will be extinguished within the receptacle and without possibility of access to the surrounding atmosphere.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a view, partly in side elevation and partly in section, of a receptacle and plug embodying the present invention, in coupled relation; Fig. 2 is a section on line 2—2 of Fig. 1,

parts of the shield and of the plug being broken away, and the shield and the plug being shown in the positions which they occupy at the end of the first step in making a connection instead of at the end of final step as in Fig. 1; Fig. 3 is a section on line 3—3 of Fig. 1, showing the parts in the same positions which they occupy in Fig. 1; Fig. 4 is a section on line 4—4 of Fig. 3; Fig. 4a is a view of a portion of Fig. 4 on an enlarged scale with the plug and receptacle in a different position; Fig. 5 is an elevation of one end of the plug member; Fig. 6 is a section taken on line 6—6 of Fig. 3; Fig. 7 is a section taken on line 7—7 of Fig. 4; and Fig. 8 is a rear view of the rotatable shield in the receptacle, removed from the latter.

In the drawings I have illustrated only a single preferred embodiment of my invention and shall confine the detailed description to that particular embodiment; it being understood that the principle of the invention may be employed in forms or constructions differing greatly in detail from the particular construction illustrated.

In the drawings, 1 is a sturdy body of insulating material, the main portion of which is in the form of a cylindrical block. At one end of the cylindrical portion of the member 1 are diametrically opposed thick lugs or ears 2. The member 1 is supported from a member 3 which may be a strong face plate, box cover or a housing or a portion of a housing. The insulating block lies behind the member 3, being supported therefrom by suitable brackets 4, 4 projecting rearwardly from the member 3 and fastened to the ears 2, 2. The free end of the cylindrical part of the member 1 projects forwardly into an opening in the member 3, preferably into the bore in a tubular hub or projection 5, on the front side of the member 3. The bore in the part 5 is larger in diameter than the external diameter of the cylindrical block.

The member 1 has a plurality of passages extending throughout the length thereof, these passages being parallel to and spaced at equal distances from the central axis of the member 1. In the arrangement shown, there are four of these passages, each indicated by the reference numeral 7. The rear end of each of the passages 7 is enlarged in diameter and contains a stationary contact in the form of a metal sleeve 8 fitting tightly therein; the internal diameter of the sleeves being equal to the diameter of the front ends of the passages 7. Each of the stationary contacts is connected to a corresponding

terminal 9 mounted on the inner or rear end of the member 1.

Resting against the front end or face of the member 1 is a thick disk 11 of insulating material of the same diameter as the cylindrical part of the member 1. The disk has on the rear or inner side a cylindrical hub 12 that fits rotatably in a recess or socket 13 in the front end of the member 1. The disk is held to the member 1, 10 while rotatable thereon, by a shaft or stem 14 extending throughout the length of the member 1 at the central axis of the latter and having at the forward end a screw-threaded part 15 that engages with a nut 16 molded in the disk or shield 11. The rear end of the shaft or stem 14 lies in an enlarged chamber 17, in the member 1. A collar 18 on the shaft or stem 14 engages with the wall at the forward end of the chamber 17 and serves to prevent lengthwise movement of 20 the shaft or stem in the forward direction, while the disk or shield 11 prevents the shaft or stem from being withdrawn in the rearward direction until it is unscrewed from the disk or shield. Surrounding the rear end of the shaft or stem 14, 25 within the chamber 17, is a torsion spring 19 one end, 21, of which is engaged in a slot 22 in the shaft or stem and the other end of which, 23, is entered into a longitudinal groove 24 cut into one wall of the chamber 17. On the rear side of the 30 disk or shield 11, adjacent to the periphery, is a segmental lug 25 projecting into a segmental notch 26 in the front end of the member 1. Consequently, the shield or disk can turn through an annular distance determined by the proportions 35 of the lug 25 and the notch 26. The spring 19 is under an initial tension and tends constantly to hold the lug 25 at one end of the notch 26, namely the righthand end as viewed in Fig. 7. The disk or shield 11 has four round openings 27 40 extending through the same parallel with the longitudinal axis of the device. These openings are of the same diameter as the forward ends of the passages 7 in the member 1, and they are correspondingly located with respect to the longitudinal axis of the device. Normally, when free to do so, the spring 19 holds the disk or shield in the position illustrated in Fig. 2, so that the openings 27 are out of registration with the passages 7 and these passages are covered by solid portions 45 of the shield. At this time the lug 25 is in engagement with a wall or shoulder at the righthand end of the notch 26. Thus, access to the stationary contacts 8 is entirely cut off from the front of the receptacle. When the shield is turned in the 50 clockwise direction through an angle of 45°, the openings 27 are brought into registration with the passages 7, and contact fingers may be passed through the openings 27 and the forward ends of the 55 passages 7 and be engaged with the stationary contacts 8.

The plug member that cooperates with the receptacle may be of any suitable form. In the arrangement shown, it comprises a long, cup-shaped casing 28 whose open end is of the same 60 external diameter as the internal diameter of the tubular hub 5, so that the casing may be inserted in the hub. The internal diameter of the plug casing is slightly greater than the external diameters of the shield and the cylindrical portion 65 of the member 1 so that, when the plug casing is inserted in the hub, it surrounds the shield and the larger part of the cylindrical portion of the member 1 as shown in Figs. 1 and 4. The plug casing has an external annular flange 29 70 between the ends thereof for engagement with 75

the forward edge of the hub and limiting the extent of entry of the plug device into the receptacle. The interior of the plug casing, for a distance inwardly from the open end somewhat greater than the distance to which the member 1 and its shield are designed to enter the casing when a connection is made, is left unobstructed, except for the presence of four long contact fingers 31 arranged parallel with the long axis of the device and located with respect to that 10 axis in a manner to correspond with the locations of the openings 27 and the passages 7. 5

With the shield 11 in its normal position, as shown in Fig. 2, upon aligning the contact fingers 31 with the openings 27, the plug device may be 15 partially entered into the receptacle. Even if no other means were provided for that purpose, the fingers themselves would serve as stops by coming in contact with the front face of the member 1. However, as will hereinafter be explained, the 20 plug casing and the hub 5 are provided with co-operating shoulders that allow the fingers initially to enter only a short distance into the openings 27, as indicated in Fig. 4a. If, then, the plug device is turned in the clockwise direction, as 25 viewed in Fig. 2, the openings 27, and the contact fingers therein, are brought into alignment with the passages 7 in the member 1 shown in Fig. 7. Now the plug may be pushed in until the contact fingers enter the tubular stationary 30 contacts 8, as shown in Fig. 4.

It is advisable that the casing of the plug device be interlocked with the shield in addition to the interlocking due to the presence of the contact fingers in the openings 27, so that the contact fingers are not subjected to the duty of turning the shield. It is also desirable that the casing of the plug device be interlocked with the member 3 of the receptacle or its hub, so that the contact fingers may not be withdrawn from the 40 shield except when the latter is in its normal position in which it dead-ends the receptacle. The interlocking of the plug casing with the rotatable shield, for driving purposes, may be conveniently accomplished by providing the shield with a peripheral notch 32 adapted to be engaged by the head 33 of a rivet passing through and fixed in the tubular wall of the casing near the open end of the latter, as best shown in Figs. 2, 6 and 8. When it is desired to insert the plug into 50 the receptacle, the rivet head is aligned with the notch or groove 32, at which time the contact fingers are aligned with the openings 27, as indicated in Fig. 2. Upon turning the plug, the rivet head acts as the driving member for turning the shield. So that there will be no obstruction in the path of the rivet head when the plug is finally pushed home into the receptacle, the cylindrical portion of the member 1 is provided with a longitudinal, peripheral groove 34 which 55 is normally out of registration with the groove 32 as indicated in Fig. 2, but which registers with the groove 32, as indicated in Fig. 6, after the shield has been turned to register its openings with the passages or openings in the member 1. 60

The interlock between the casing or housings of the plug and the receptacle may conveniently consist of a Z-shaped groove 35 in the periphery of the plug casing; this groove comprising a long longitudinal portion extending from the flange 70 29 to within a short distance of the open end of the casing, a circumferential section extending from the front or outer end of this long leg parallel with the front edge of the casing, and then a short leg extending in the longitudinal 75

direction and opening out through the edge of the casing at the open end of the latter, as best shown in Fig. 5. Cooperating with the groove 35 is the head 36 of a rivet fixed in the wall of the tubular hub 5, as best shown in Figs. 1 and 2. The parts are so located that the plug can be entered in the hub of the receptacle only when the short longitudinal leg of the groove 35 is brought into registration with the rivet head 36, at which time the rivet head 33 is in registration with the groove or notch 32 in the shield, and the contact fingers 31 are aligned with the openings 27 in the shield. Therefore, in making a connection, the plug and the receptacle are properly aligned through the rivet head 36 and the inlet end of the groove 35, whereupon the plug may be pushed in until it is interlocked with the rotatable shield; then the plug may be turned, carrying the shield along with it until the openings 27 are aligned with the passages 7 as in Fig. 4a; and, finally, the plug may be pushed in so as to engage its fingers with the stationary contacts in the receptacle, as in Fig. 4; all three of these movements of the plug being under the guidance of the pin and groove connection between the plug casing and the tubular hub or the receptacle.

After a connection has been completed, the separation of the plug from the receptacle can be effected only by reversing the three-step movement of the plug; the first step consisting in withdrawing the plug lengthwise through the long longitudinal leg of the Z-shaped groove, which results in drawing the contact fingers of the plug out of engagement with the stationary contacts 35 and far enough away from the latter, as in Fig. 4a, to insure that any arcs that are created between the separating contact elements will be extinguished. This straight lengthwise movement must of course carry the contact fingers out far enough so that they are entirely clear of the member 1 and thus make it possible for the protective shield to be turned. After the plug has been withdrawn to the extent just described, it may be rotated to shift the contact fingers from the relative angular positions which they occupy in Fig. 3 to the angular positions of Fig. 2; this angular movement being limited by the length of the circumferential section of the groove 35 and causing the ends of the passages 7 in the member 1 to be completely covered as in Fig. 2. The final withdrawal of the plug is permitted by the short leg of the groove 35, and serves simply to withdraw the plug completely from the receptacle and the rotary shield which then remains in its normal protective position, being held there by the spring.

Since the rotatable disk or shield 11 is not intended to take the place of the ordinary door or cover, with which receptacles are often provided, any usual or suitable door 37 may be mounted on the receptacle in position to extend across the open end of the tubular hub and close the same when the plug is withdrawn.

It is advisable effectively to ground the external metal parts of the plug when operatively engaged with the receptacle. To this end I have arranged in a longitudinal peripheral groove 38 in the periphery of the cylindrical body portion of the member 1, which also continues as a tunnel through one of the lugs 2, a spring finger 39, one end of which may conveniently be held in place by the screw 40 that fastens the lug to the corre-

sponding bracket 14. The free end of this spring finger is adapted to project slightly beyond the periphery of the cylindrical part of the member 1 and be so shaped that when the plug is inserted, the finger enters the open end of the plug casing and is pressed down into the groove more or less, thereby causing it to make a good, wiping contact with the inner surface of the surrounding casing. This spring finger may be grounded through the screw, the bracket and the casing or housing for the receptacle, or in any other suitable manner. Also, if desired, the grounding devices just described may be provided in duplicate, as illustrated in Fig. 1.

It will thus be seen that I have produced a simple and novel construction in which one of the members of a plug and receptacle combination is automatically dead-ended upon separation of such member from each other, in which the arcs created in breaking the circuits are formed and extinguished in closed chambers and cannot set to ignite combustible gases in the atmosphere surrounding the device, and the metal casings or other external elements are effectively grounded.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. In combination, a receptacle and a plug separable from each other by relative lengthwise movement, contacts in the receptacle, a rotatable shield of insulating material in front of said contacts and adapted in one angular position to cover the same, said shield having openings adapted in a second angular position to register with and expose said contacts, contact fingers on the plug adapted to be inserted through said openings and then be engaged with said contacts by a lengthwise movement while the shield is in said second angular position, and interlocking shoulders on the receptacle and the plug to compel the plug to move with the shield into the first of the said angular positions of the latter before the contact fingers on the plug can be withdrawn from the openings in the shield after a connection has been made.

2. In combination, a receptacle and a plug separable therefrom, said receptacle including a body member of insulating material having passages extending into the same through the front face, contacts in said passages, a shield of insulating material engaged with the front face of said body member, means to support said shield for angular movements on said body member, said shield having openings therein which in one position of the shield register with said passages and in a second position of the shield leave said passages covered by the shield, spring means tending constantly to hold said shield in said second position, contact elements on the plug adapted to be inserted through said openings and to enter said passages and be engaged with said contacts, and shoulders on the shield and the plug interlocking with each other to hold them against relative rotary movements while the said fingers are engaged in said openings and clear of said passages.

NILS A. TORNBLOM.
